(57) **CLAIM**

The ornamental design for an adaptive clothing garment, as shown and described.

DESCRIPTION

FIG. 1 is a rear and right-side perspective view of an adaptive clothing garment.

FIG. 2 is a rear and right-side perspective view of the adaptive clothing garment of FIG. 1 with a rear flap lifted. FIG. 3 is a rear and right-side perspective view of the adaptive clothing garment of FIG. 1 with both rear flaps lifted.

FIG. 4 is a front view of the adaptive clothing garment of FIG. 1.

FIG. 5 is a rear view of the adaptive clothing garment of FIG. 1.

FIG. 6 is a right-side view of the adaptive clothing garment of FIG. 1.

FIG. 7 is a left-side view of the adaptive clothing garment of FIG. 1.

FIG. 8 is a top view of the adaptive clothing garment of FIG. 1; and,

FIG. 9 is a bottom view of the adaptive clothing garment of FIG. 1.

The longer broken lines in FIG. 3 depict environment around the adaptive clothing garment that form no part of the claimed design. The shorter broken lines in FIG. 3 and the broken lines in FIGS. 1, 2, and 4-9 depict stitching of the adaptive clothing garment that form part of the claimed design.

1 Claim, 8 Drawing Sheets
